REFRIGERATING APPARATUS

Frank Conrad, Wilkinsburg, and Christian Aalborg, Pittsburgh, Pa., assignors to Westinghouse Electric and Manufacturing Company, a corporation of Pennsylvania

Original application July 8, 1927, Serial No. 204,401. Divided and this application March 27, 1930, Serial No. 439,408

9 Claims. (Cl. 230—58)

Our invention relates to refrigerators and more particularly to refrigerators of the compression type and of small capacity, such as are suitable for household use, and it has for an object to provide apparatus of the character designated which shall operate more effectively, quietly, efficiently and reliably than apparatus of this character heretofore constructed.

Our invention has for a further object to provide a refrigerator in which all of the working or moving parts are entirely enclosed in a hermetically sealed casing, whereby leakage of the refrigerant fluid, as well as lubricant, is prevented.

These and other objects, which will be made apparent upon the further description of our invention, may be attained by the employment of the apparatus hereinafter described and illustrated in the accompanying drawings, in which:

Figure 1 is a view, in sectional elevation, showing one form of refrigerator arranged in accordance with our invention;

Fig. 2 is a sectional view, taken on the line II—II of Fig. 3, of the compression unit shown in Fig. 1;

Fig. 3 is a sectional view taken on the line III—III, of Fig. 2;

Figs. 4 and 5 are partial, sectional views taken on the lines IV—IV and V—V of Fig. 3, respectively;

Fig. 6 is a view, in elevation, of that portion of the compressor unit shown in Fig. 5.

Our invention provides a form of refrigerating machine in which all the moving or working parts are totally enclosed, but which, at the same time, permits the compressor and motor unit, as well as the condenser, to be so located, with respect to the refrigerator box structure, that they are entirely hidden from view, so that the appearance of the entire refrigerating unit may always be of the highest order. We accomplish the foregoing by providing a hermetically sealed compressor-motor unit in a bottom or lower compartment of the refrigerator box structure, the unit being so arranged that the heat generated by both the compressor and the motor is radiated through the walls of the enclosing casing. In addition, the condenser is preferably located upon the rear wall of the box and is arranged to have a natural draft circulation of air thereto for absorbing the heat of condensation of the refrigerant vapor. In this way, the motor-compressor unit, as well as the condenser unit, may be properly cooled without requiring any external fan, or separate motor for driving the fan.

At the same time, the motor-compressor unit, as well as the condenser, are so located that they are not exposed to view and, consequently, do not detract from the appearance of the refrigerator box structure.

This application relates particularly to the structure of the motor-compressor unit utilized in our improved refrigerating apparatus and is a division of our copending application, Serial No. 204,401, filed July 8, 1927 for Refrigerators.

Referring now to the drawings for a more detailed description of our invention, we show in Fig. 1 a refrigerator box structure 10, embodying front and rear walls 11 and 12. Located in the upper portion of the refrigerator box structure is a cooling or food storage compartment 13, and located in the lower portion is a machinery compartment 14. The cooling compartment 13 is provided with an access door 15 in the usual manner, while the machinery compartment 14, is preferably provided in all of its walls, except the rear wall, with suitable ventilating openings or louvers 16. The rear wall of the machinery compartment may be left entirely open except for the box supporting structure 17 and the machinery supporting structure 18.

Located within the machinery compartment 14 is a compressor-motor unit 19 which is supported upon a suitable bracket 20 carried by the machinery supporting structure 18. Also supported upon the machinery supporting structure 18 and located upon the rear wall 12 of the box is a condenser 21, while disposed within the cooling compartment 13 is the cooling element or evaporator 22. The evaporator 22 is supported upon a removable portion 23, forming a part of the rear wall and carried by the supporting structure 18, the opening in the rear wall being sufficient to permit the evaporator 22 to be withdrawn therethrough. From the foregoing description, it will be apparent that the motor-compressor unit 19, condenser 21 and the evaporator 22, together with the machinery supporting structure 18, may be entirely removed from the refrigerator box structure as a single unit. This is especially advantageous in servicing the machine as the entire machinery may be readily replaced although its different elements are located in relatively different portions of the box structure. Such an arrangement does not require that the motor-compressor unit, condenser and evaporator be arranged in contiguous relation, such as is customary in refrigerating machines wherein the motor-compressor unit, as well as the condenser, are located upon the top of the box structure.

with the cooling element depending therefrom and extending into the cooling compartment. In other words, the arrangement disclosed herein provides every advantage from a servicing standpoint while permitting the various elements of the refrigerating system to be located in those portions of the refrigerator box structure which are best suited from all considerations.

Reference is now made to Figs. 2 to 6, inclusive, for a detailed description of the motor-compressor unit 19. As shown in Fig. 2, we provide a casing 31 consisting of a central cylinder or sleeve member 32 equipped at its respective ends with suitable closures 33 and 34. The closures 33 and 34 are retained against the cylinder 32 by means of flange rings 35 and tension members or bolts 36 spaced circumferentially about the cylinder 32 and so arranged as to hold both the closures 33 and 34 in fluid-tight engagement with the central cylinder 32. Suitable gaskets or soldering strips 37 may be provided between the enclosures and the cylinder for insuring a hermetic seal.

Provided within the cylinder 32 is a partition wall or spider 38 dividing the casing 31 into, what may be termed, a motor-chamber 39 and a compressor-chamber 41. Located within the motor chamber 39 is a motor 40 having its stationary element 41 supported directly in the cylinder 32 and its rotating element 42 connected by means of an annular cup-shaped member 43 to a drive shaft 44. The latter is retained in suitable bearings 45 and 46 provided in a longitudinally extending sleeve 47 formed upon the partition wall 38.

Located within the compressor chamber 41 is a compressor 51 which is of the reciprocating, oscillating cylinder type. The compressor 51 comprises essentially a crank pin 52 provided on one end of the drive shaft 44. Operatively connected to the crank pin 52 is a piston rod 53 rigidly secured to a piston 54. Associated with the piston 54 is a cylinder 55 arranged to oscillate upon a journal 56 located in a face plate 57. The face plate 57 forms with a portion of the partition 38 a suction chamber 58 having a refrigerant vapor inlet 59, shown in Fig. 3. Suitable inlet ports 61 are provided in the face plate 57, as well as the cylinder 55, for permitting the admission of refrigerant vapor to the latter, while suitable discharge ports 62 are located oppositely in the cylinder. Suitable discharge valves 63 of the spring-flap type are associated with the discharge ports 62.

The cylinder 55 is retained in bearing engagement with the face plate 57 by means of a yoke 64. As shown in Figs. 5 and 6, the yoke 64 is composed of suitable lugs 65 provided on the partition wall 38, and a bridge plate 66 secured to the lugs by means of screws or bolts 67. The cylinder 55, as well as the bridge plate 66, are provided with cooperative journal portions 68 which together with the journal 56 maintain the axis of oscillation of the cylinder. A spring 69 is interposed between the bridge plate 66 and the cylinder 55 for retaining the latter at all times in bearing engagement with the face plate 57.

Referring again to Figs. 2 and 3, the lower portion of the partition wall 38 is provided with drainage holes 71 for permitting the passage of lubricant, while located in the upper portion of the partition wall 38 is a suitable opening 72 for permitting the passage of refrigerant vapor.

Provided in the upper portion of the casing is a compressed refrigerant vapor outlet 70.

Secured to the compressor end of the drive shaft 44 is a pinion 73 which meshes with a gear 74 journaled upon a pin 75 fixed in the partition wall 38, as shown particularly in Fig. 4. The pinion 73 and the gear 74 are utilized for effecting a splash system of lubrication for the working parts of the compressor and the motor, a level of lubricant being normally maintained in the casing such as indicated at 76 in Fig. 3. Provided in the compressor chamber 41 and disposed about the pinion and gear 73 and 74, as well as the compressor, is a baffle 77 which defines with the casing 31 a lubricant splash chamber 78. The lower portion 79 of the baffle 77 is preferably perforated so that the foreign particles are prevented from reaching the gear 74.

As shown in Fig. 3, the axis of the compressor is inclined at a slight angle below the horizontal but above the level of the lubricant, the pinion 73 and the gear 74 being utilized to splash the lubricant upon the working parts of the compressor. The gear 74 is preferably constructed of some material, such as fiber, which will insure silent operation. The pinion 73 is provided with a counter-weighted portion 79 so arranged as to compensate for the unbalance created by rotation of the crank pin.

Lubricant is conveyed to the bearings 45 and 46 by means of spiral grooves 81 provided in the drive shaft 44, the lubricant discharged from the bearing 45 being returned to the lubricant chamber 78 by a passage 82 located in the sleeve 47. Lubricant is conveyed to the cylinder 55 by means of passages 83 and 84 provided in the connecting rod 53 and the piston 54, respectively. Suitable supporting feet 85 are provided on the cylinder 32 for supporting the entire unit upon the bracket 20.

As shown in Fig. 1, a conduit 115 is provided for conveying refrigerant vapor from the outlet 70 of the motor-pump unit 19 to the intake manifold 91 of the condenser. A conduit 116 is provided for conveying the condensed refrigerant to the inlet of the expansion valve 103, while the refrigerant vapor withdrawn from the expansion coil is conveyed by conduit 117 to the inlet 59 of the motor-pump unit 19.

From the foregoing description, the operation of our refrigerator will be apparent. The refrigerator is first charged with a suitable refrigerant, such as methyl chloride, and a suitable lubricant, such as mineral oil. Upon the motor 40 being connected with a source of electrical energy, the compressor 51 is actuated and a reduction in pressure in the expansion coil 106 is effected, resulting in vaporization of the liquid refrigerant passing therethrough and in the absorption of heat from the evaporator 22, as well as from the interior of the cooling chamber 13. The refrigerant vapor generated in the expansion coil 106 is withdrawn through the conduit 117 to the inlet chamber 58 of the motor pump unit 19. The refrigerant vapor enters the cylinder 55 of the compressor when the intake ports 61 in the face plate and in the cylinder are in communication. It is compressed and discharged through the discharge ports 62 and spring valves 63 to the interior of the casing 31. In other words, the discharge pressure of the compressor prevails throughout the interior of the casing 31. The heat generated by the compressor is thus dissipated through the intermedia-

ary of the refrigerant vapor to the walls of the casing while the motor heat is radiated directly through the walls of the casing.

Compressed refrigerant vapor leaves the casing 34 through the outlet 70 and enters the intake manifold 91 of the condenser. The refrigerant vapor passes through the condenser 21, and sufficient heat is absorbed to effect condensation, the condensate draining into the 10 lower portion of the condenser and leaving it through the outlet manifold 92. Upon accumulation of a predetermined pressure in the condenser, the expansion valve 103 opens to permit the condensed refrigerant to enter the expansion coil 106 in a manner well understood in the art.

Lubrication of the compressor mechanism is effected in a novel manner by means of the pinion 13 and gear 14 which continually splash 20 lubricant about the lubricant chamber 78. The lubricant is thus deposited upon the various working parts and is afterwards returned to the lower portion of the casing. Suitable ducts 81 are provided for insuring positive lubrication 25 of the bearings 45 and 46, while the ducts 83 and 84 insure thorough lubrication of the compressor cylinder. We have found a lubricating system of the splash type to be extremely reliable and effective for thoroughly lubricating the compression 30 mechanism of refrigerators, especially of those types in which the compression mechanism is totally enclosed.

From the foregoing, it will be apparent that we have invented a novel form of refrigerating apparatus which embodies no external moving or 35 working parts. The entire apparatus is hermetically sealed so that the possibility of leakage of either oil or refrigerant is eliminated. At the same time, the various essential elements of 40 the refrigerating system are located in those portions of the refrigerator box structure which are most desirable from not only an operating but a sanitary and commercial standpoint, and at the same time the arrangement is such that 45 the entire refrigerating apparatus may be readily removed from the refrigerator box structure to permit ready servicing.

While we have shown our invention in but one form, it will be obvious to those skilled in the 50 art, that it is not so limited, but is susceptible of various changes and modifications, without departing from the spirit thereof, and we desire, therefore, that only such limitations shall be placed thereupon as are imposed by the prior 55 art or as are specifically set forth in the appended claims.

We claim as our invention:

1. In a compression refrigerating apparatus, the combination with a compressor and a motor 60 for driving the compressor, of a fluid-tight casing for enclosing the motor and the compressor comprising a central cylinder, end caps bearing against the cylinder, flange rings bearing against the end caps, and a plurality of tie bolts spaced 65 circumferentially about the cylinder and engaging the flange rings for clamping the end caps and the cylinder together.

2. In a compression refrigerating apparatus, the combination with a compressor and a motor 70 for driving the compressor, of a fluid-tight casing for enclosing the motor and the compressor comprising a central cylinder having an intermediate partition for dividing said cylinder into a compressor chamber and a motor chamber, a removable end cap provided at one end of the cylinder

for permitting access to the compressor chamber, a removable end cap provided at the other end of the cylinder for permitting access to the motor chamber, flange rings bearing against each of the removable end caps, and tension members engaging the flange rings for clamping the end caps and the cylinder together.

3. In a compression refrigerating apparatus, the combination of a fluid-tight casing, partition means dividing the casing into a motor chamber and a compressor chamber, a motor disposed in the motor chamber, a compressor disposed in the compressor chamber, a drive shaft for connecting the motor to the compressor, a baffle disposed within the compressor chamber about the compressor and the drive shaft and defining with the casing a lubricant chamber, and gear means rotated by the drive shaft for transmitting lubricant to the working parts of the compressor and the motor.

4. In a compression refrigerating apparatus, the combination of a fluid-tight casing, partition means dividing the casing into a motor chamber and a compressor chamber, a motor disposed within the motor chamber, a compressor disposed within the compressor chamber, a shaft connecting the motor to the compressor, a plurality of bearings for the shaft, a baffle structure disposed within the compressor chamber about the shaft and the compressor and defining with the casing a lubricant chamber, means driven by the drive shaft and disposed within the lubricant chamber for transmitting lubricant to the working parts of the compressor and to the shaft bearings, and means for returning lubricant discharged from the shaft bearings to the lubricant chamber.

5. In a refrigerating apparatus, the combination of a compressor housing containing a body of lubricant, a horizontal drive shaft disposed within the housing above the level of the lubricant, a compressor of the oscillating cylinder type operatively connected to the drive shaft, said compressor having its axis of oscillation disposed below the shaft but above the level of the lubricant, and means driven by the drive shaft and extending into the body of lubricant for transmitting lubricant to the working parts of the compressor.

6. In a refrigerating apparatus, the combination of a housing, a drive shaft in the housing, a crank pin provided on the drive shaft, a compressor of the reciprocating type operatively connected to the crank pin, and a gear for supplying lubricant to the working parts of the compressor provided on the drive shaft in the vicinity of the crank pin, said gear having a counterweighted portion arranged to compensate for the unbalance created by the rotation of the crank pin.

7. In a refrigerating apparatus, the combination of a longitudinally disposed, cylindrical, fluid tight casing, a motor disposed in one end of the casing, a compressor disposed in the other end of the casing, said compressor being arranged to discharge compressed refrigerant into the interior of the casing, a refrigerant intake conduit connecting with the compressor, a horizontal drive shaft connecting the motor to the compressor, a baffle structure disposed about the shaft and the compressor and defining with the casing a lubricating chamber, and means driven by the shaft and located in the lubricant chamber for maintaining a splash system of lubrication for the working parts of the compressor and the motor.

8. In a refrigerating apparatus, the combination of a motor, a compressor, a longitudinally dis-

posed substantially cylindrical fluid-tight casing enclosing the motor and compressor, partition means within the casing and defining with the casing a compartment for the motor and a compartment for the compressor, a substantially horizontal drive shaft connecting the motor with the compressor, said compressor compartment providing a reservoir for a body of lubricant, means provided on the drive shaft in the compressor compartment for splashing lubricant from the reservoir to the working parts of the compressor, means for conveying a portion of the splashed lubricant along the drive shaft in a direction from the compressor to the outer end of the motor, whereby to lubricate the motor bearings, and means passing through the partition and extending from the end of the motor to the lubricant reservoir in the compressor compartment for returning lubricant from the outer motor bearing to the lubricant reservoir.

9. In a refrigerating apparatus, the combination of a motor, a compressor, a longitudinally disposed substantially cylindrical fluid-tight cas-

ing enclosing the motor and compressor, partition means within the casing and defining with the casing a compartment for the motor and a compartment for the compressor, a substantially horizontal drive shaft connecting the motor with the compressor, said partition means having formed therewith a bearing support for the drive shaft, said compressor compartment providing a reservoir for a body of lubricant, means on the drive shaft in the compressor compartment for splashing lubricant from the reservoir to the working parts of the compressor, means for conveying a portion of the splashed lubricant along the drive shaft in a direction from the compressor to the outer end of the motor whereby to lubricate the motor bearings, and means passing through the partition and extending from the end of the motor to the lubricant reservoir in the compressor compartment for returning lubricant from the outer motor bearing to the lubricant reservoir. 5 10 15 20
